UNITED STATES PATENT OFFICE.

CHARLES L. PEIRCE, JR., OF CHICAGO, ILLINOIS, ASSIGNOR TO PEIRCE SPECIALTY COMPANY, OF CHICAGO, ILLINOIS, A CORPORATION OF ILLINOIS.

INSULATOR.

No. 856,801.

Specification of Letters Patent.

Patented June 11, 1907.

Application filed January 29, 1906. Serial No. 298,475.

To all whom it may concern:

Be it known that I, CHARLES L. PEIRCE, Jr., a citizen of the United States, residing at Chicago, in the county of Cook and State of Illinois, have invented certain new and useful Improvements in Insulators, of which the following is a specification.

Insulators for electricity, especially for telephone and telegraph wires, generally consist of a bracket secured to a suitable support, and provided with a wooden peg to which is attached a glass or other form of insulator. There are certain well known objections to this form of structure such as the breaking of the insulator, due to the contraction of the glass in cold weather or a consequent loosening in warm weather, or through vibration of the wire. In my construction I overcome these results by the combination of a bracket, preferably made of a channel bar or strip, and a spring metal strip provided with a screw-threaded exterior surrounding and secured to the bracket, the holding means for the strip being accomplished by providing ears thereon, slotting the end of the bar, inserting the ear in the slot, when the strip is in set position, and then swaging over the end of the bar to firmly clamp the ears therein. This construction not only serves as a holding means but also gives a taper to the strip, as the bar is made somewhat narrower at its upper end by the formation of the slot.

Referring to the drawing Figure 1 is an elevational view of my device in the preferred form with one end of the bracket broken away; Fig. 2 is a top view of Fig. 1; Fig. 3 is a plan view of the metal strip; Fig. 4 is an edge view of the metal strip; Fig. 5 is a front elevational view of the channel bar, one end being broken away and designed to show a single slot and the ears; Fig. 6 is a top view of the assembled device when made according to Fig. 5; and Fig. 7 is an elevational view of my device applied to a bracket.

8 represents a piece of channel bar in the form of a bracket, having at its end a cut-away portion 9 to form the ears 10 and 11, and provided with slots 12 and 13 [Figs. 1 and 2], in the preferred form, although a single slot 14 [Fig. 5] might be employed.

15 is a strip of sheet metal, corrugated to provide an exterior screw threaded surface 16 and 17 and carrying the ears 18 and 19

formed by cutting away obliquely the end portions of the strip, as shown at 20 and 21, 55 which also gives a taper to the strip when coiled.

To construct the device in the preferred form one of the bars on the spring metal strip is inserted in the slot, say 12, and the strip is 60 then bent out of the channel and around the bar the other ear being inserted into the slot 13. The ears 10 and 11 are then swaged in, clamping the ears 18 and 19 within the slots and thus firmly securing the strip against a 65 longitudinal or rotating movement relative to the support, or the strip may be formed independently to fit the bar and passed over its head, sliding down upon the same until its ears are set in the slot and then secured in the 70 usual manner.

In my modified form I provide only one slot in which the ears are secured in the same manner as shown in Figs. 1 and 2. The many advantages of this construction, are 75 obvious; for it permits a very thin piece of strip metal to be used, due to the large bearing surface afforded by the channel bar and upon which the metal strip rests, and the channel bar in turn allows the ready formation of the slots or slot. It is also obvious that in place of the channel bar a T-bar might be used which would likewise permit a slot to be easily formed therein and at the same time give a three-point bearing surface 80 for the metal strip.

Having now fully described my invention what I claim and wish to secure by Letters Patent is:

1. In combination with an insulator, a 90 bracket formed of a metal bar provided with a slot in one of its sides, and a sheet metal strip surrounding said bar and having one of its ends secured in said slot, substantially as described.

2. In combination with an insulator, a bracket formed of a channel bar and provided with slots, a sheet metal strip adapted to substantially surround said bar and provided with ears to enter said slots, and means 100 for securing said strip to said bar, substantially as described.

3. In combination with an insulator, a bracket formed of a channel bar and provided with slots, an elastic sheet metal strip 105 formed to have a threaded exterior and

adapted to surround said bar, and means for retaining said strip within said slots and around said bar, substantially as described.

4. In combination with an insulator, a bracket formed of a channel bar having ears formed on its end and provided with slots, and a spring metal strip formed to have a threaded exterior and provided with ears

entering said slots and retained therein by swaging over said ears on said bar, substantially as described.

CHARLES L. PEIRCE, JR.
